UNITED STATES PATENT OFFICE

SAMUEL H. PAGE, OF STRATFORD, CONNECTICUT, ASSIGNOR TO THE AMERICAN FABRICS COMPANY, OF BRIDGEPORT, CONNECTICUT, A CORPORATION OF CONNECTICUT

DESIGN FOR A LACE

Application filed March 24, 1931. Serial No. 39,226. Term of patent 7 years.

To all whom it may concern:

Be it known that I, SAMUEL H. PAGE, subject of the King of Great Britain, residing at Stratford, county of Fairfield, State of Connecticut, have invented a new, original, and ornamental Design for a Lace, of which the following is a specification, reference being had to the accompanying drawing, forming part thereof.

The figure is a plan view of a piece of lace showing my new design.

The dominant characteristic of this design is the large open mesh effect caused by the symmetrical arrangement of the oval openings which by contrast throw the woven design into positive relief.

I claim:

The ornamental design for a lace substantially as shown and described.

SAMUEL H. PAGE.
